COMBINED POTTY-CHAIR AND BASE

Richard L. Panicci, Hanover, Mass., assignor to
Kiddie Products, Inc., Squantum, Mass.

Continuation-in-part of design application Ser. No.
258,926, June 1, 1972. This application Aug. 17,
1973, Ser. No. 389,350

Term of patent 14 years

Int. Cl. D23—02

U.S. Cl. D23—53

FIG 1

FIG. 3

FIG. 2

FIG. 1 is a front perspective view of a combined potty-chair and base showing my new design;

FIG. 2 is a rear perspective view thereof; and

FIG. 3 is an elevational view taken from the side opposite that shown in FIGS. 1 and 2.

This is a continuation-in-part of design application Ser. No. 258,926, filed June 1, 1972.

I claim:

The ornamental design for a combined potty-chair and base, as shown.
